UNITED STATES PATENT OFFICE

2,503,019

STORM SASH VENTILATOR

Michael J. Zinner, Milwaukee, Wis.

Application February 4, 1949, Serial No. 74,627

3 Claims. (CL. 98—97)

1

My invention relates to storm sash ventilators and more particularly to means for ventilating enclosures or rooms provided with windows equipped with storm sashes.

The object of my invention is to provide a means for covering an aperture of any size or contour with a screen and closing means constructed in a simple manner to enable the assembled unit to be attached with the aid of two screws.

Another object of my invention is to provide a storm sash ventilator that is a self-contained unit and may be sold as an accessory, may be easily and economically manufactured, and yet be efficient for the purpose for which it is intended.

It is manifest to anyone familiar with storm sash construction that many methods and means have been devised to permit air circulation during moderate weather. The usual procedure is to provide a plurality of apertures in alignment with one another, or an elongated slot to be cut through a portion of the storm window frame, and to provide two separate pieces, one attached stationary to the frame, another to be hingedly attached to the frame to form a cover for the openings. The device described and claimed herein is a complete unit that may be applied over the openings in the frame and provides a screen and closing means that may be attached by means of two wood screws or the like.

Other and further objects of my invention will become more apparent as the description proceeds and when taken in conjunction with the drawing in which

Figure 1 is a perspective view of the device attached to a fragmentary portion of a storm sash.

Figure 2 is a cross-sectional view of the device applied to the frame of a storm sash.

Figure 3 is a fragmentary view of the screen and screen frame.

Figure 4 is a front view of the closing portion.

Figure 5 is a fragmentary view of the assembled device.

Figure 6 is a cross-sectional view as in Figure 2, showing the screen frame channeled to support the screen, and

Figure 7 is a top fragmentary view of the closing portion.

Similar characters of reference indicate corresponding parts throughout the several views, and referring now to the same, the character 10 shows a storm sash frame which is constructed in a manner to support panes of glass shown as 11.

2

The bottom portion of the storm sash frame 10 is shown provided with an elongated slot 12. This slot may be of any size or contour, and may consist of a series of apertures in direct alignment with one another.

There is a metal frame 13 shown of angle construction in Figure 2, but may be of a channel construction as shown in Figure 6. This metal frame 13 is shown with semi-circular ends. However, it may be of any shape or contour, and is provided with a pair of cross members 14 disposed near the end of the frame 13.

There is a section of screen shown as 15 which is of the same shape and contour as the metal frame 13. This screen is disposed within the frame 13, either supported by the channel or by the angle construction, to keep it in position. There are apertures 16 shown through the cross members 14 and a closing portion which may be 20 constructed of wood or metal is shown as 17 and is hingedly supported by a screw 18 through the aperture 16 at one end of the frame 13, and a stationary member 19 forming a part of the closing portion is shown stationary attached and 25 supported by means of a screw 20 through the aperture 16 in the frame portion 13. The screws 18 and 20 may be wood screws and may enter into the wood frame of the sash 10. By tightening up these screws, the frame 13 is drawn tight 30 against the face of the sash 10.

The portions 17 and 19 may be beveled at 21 as shown in Figure 7, and the frame 13 may be provided with outwardly extending lugs shown as 22 in Figure 3. These lugs have apertures 23 35 to be used when screws are employed to fasten the frame 13 to the window sash 10, when the closing portions 17 and 19 are attached to the frame by means of screws or rivets through the apertures 16 in the frame.

40 In the chosen embodiments of my invention there are features not heretofore disclosed in the prior art, and although I have shown a particular arrangement of the component parts, I am fully cognizant of the fact that many changes in their form and configuration may be made without departing from the spirit of my invention or the scope of the appended claims.

Having thus described my invention, what I claim and desire to secure by Letters Patent in the United States is:

50 1. A device of the character described comprising an elongated channeled outer frame, a screen disposed within said frame and supported by said channels, said frame provided with transverse members near both of its ends, a stationary

closing member attached to one end of said frame and supported by one of said transverse members, a movable closing member pivotally attached to the other end of said frame and supported by the other of said transverse members, said stationary and movable members arranged to engage with one another at their depending ends, and means for attaching the assembled unit to a surface.

2. A device of the character described comprising an elongated frame forming an enclosure, a screen member of the same shape and contour as said frame disposed within said enclosure, said frame having outwardly extending attaching members integrally formed therewith, said frame further provided with transverse members near both its ends, a stationary member attached to one of said transverse members, of said frame, said stationary member having its inwardly disposed end tapered, a movable member pivotally attached to the other of said transverse members of said frame, said movable member having its depending end tapered for engagement with said stationary member.

3. A device of the character described comprising an elongated channelled outer frame, a screen

5 of the same shape and contour as said frame disposed within the frame and supported by said channels, closing means constructed of two parts, one of said parts pivotally mounted to said frame, the other of said parts of said closing means permanently attached to said frame, the depending ends of said closing portions arranged for engagement with one another at their depending ends, and means for attaching the entire assembled unit to a surface.

MICHAEL J. ZINNER.
